Primary Examiner — Ryan Harvey(74) *Attorney, Agent, or Firm* — James A. Italia; Italia IP(57) **CLAIM**

The ornamental design for a belt with inner projections, as shown and described.

DESCRIPTION

FIG. 1 is a perspective view of the belt with inner projections showing my new design;

FIG. 2 is a perspective view of the inner surface of the belt; and,

FIG. 3 is a perspective view of the outer surface of the belt. In the drawings, the broken lines are for the purpose of illustrating environmental subject matter only and form no part of the claimed invention.
